(57) CLAIM

The ornamental design for a ice cream product, as shown and described.

DESCRIPTION

FIG. 1 is a perspective plan view in accordance with our new design;

FIG. 2 is a front plan view thereof;

FIG. 3 is a rear elevational plan view thereof;

FIG. 4 is a left side plan view thereof;

FIG. 5 is a right side plan view thereof;

FIG. 6 is a top plan view thereof; and,

FIG. 7 is a bottom plan view thereof.

The broken lines in the drawings illustrate the environment of the claimed design and form no part thereof.
